UNITED STATES PATENT OFFICE.

FRED M. ALLEN, OF AUBURN, RHODE ISLAND.

AUTOMATIC FIRE-EXTINGUISHER.

SPECIFICATION forming part of Letters Patent No. 732,494, dated June 30, 1903.

Application filed April 15, 1903. Serial No. 152,665. (No model.)

To all whom it may concern:

Be it known that I, FRED M. ALLEN, a citizen of the United States, residing at Auburn, in the town of Cranston, county of Providence and State of Rhode Island, have invented a new and useful Improvement in Automatic Fire-Extinguishers, of which the following is a specification.

This invention has reference to an improvement in automatic fire-extinguishers, known in the arts as "automatic sprinklers," for automatically extinguishing fires with water or other fluids.

In automatic fire-extinguishers or sprinklers as heretofore constructed more damage is caused by the excessive flow of water through the sprinkler (after the fire has been extinguished by the sprinkler) than was caused by the fire.

The object of my invention is to prevent excessive damage by water in small fires after the fire has been extinguished by the automatic sprinklers, and I accomplish this object by the novel construction of an automatic sprinkler having two valves independently controlled by low and high temperature solders, the fusing of the low-temperature solder opening one valve and allowing a predetermined amount of water to flow through the sprinkler to extinguish a small fire. The valve is then automatically closed. If this amount of water is not sufficient to extinguish the fire, the increased heat of the fire fuses the high-temperature solder and opens the other valve, allowing a continuous flow of water through the sprinkler to extinguish the fire. After the fire is extinguished the water may be shut off from the main in the usual way.

My invention consists in the peculiar and novel construction of a double or twin sprinkler having two valves independently controlled by low and high temperature solders and means for automatically closing the low-temperature valve after a predetermined amount of water has passed through the sprinkler, as will be more fully set forth hereinafter.

Figure 1 is a sectional view taken centrally through the sprinkler, auxiliary pipe, and supply-pipe, showing the low and high temperature valves in the sprinkler and the

mechanism in the auxiliary pipe to automatically close the low-temperature valve after a predetermined amount of water has passed through the sprinkler, the open position of the low-temperature valve and the position of the mechanism in the auxiliary pipe after closing the valve being shown in broken lines. Fig. 2 is an enlarged detail sectional view taken lengthwise through the auxiliary pipe and the automatic valve-closing mechanism; and Fig. 3 is a transverse sectional view taken on line X-X of Fig. 2, showing the motor for operating the valve-closing mechanism.

In the drawings, *a* indicates the sprinkler, *b* the auxiliary pipe, and *c* the supply-pipe, the sprinkler being connected to the auxiliary pipe by the elbow *b*¹⁷. The sprinkler *a* has the inlet-opening *a*¹, branching into the valve-opening *a*², controlled by the valve *a*³, and the valve-opening *a*⁴, controlled by the valve *a*⁵, the valves having seats formed in the body of the sprinkler in the usual way. The opening of the valve *a*³ or *a*⁵ allows the water to pass through the valve-opening *a*² or *a*⁴, the chamber *a*⁶, and the nozzle *a*⁷, when it strikes the deflector *a*⁸, secured on the end of the nozzle by the frame *a*⁹. The valve-chambers *a*¹⁰ *a*¹⁰ are placed at an angle to each other and have their upper ends closed by the caps *a*¹¹ *a*¹¹, screw-threaded into the ends of the chambers. The valve-stems pass through the holes in the caps and have nuts secured on their ends, and between these nuts and the caps the spring-washers *a*¹² *a*¹² are placed to assist in opening the valves. The levers *a*¹³ *a*¹³ are pivotally secured at one end to the nozzle *a*⁷ of the sprinkler and bear on the ends of the valve-stems and are secured in their closed position by the hooked ends *a*¹⁴ *a*¹⁴, passing under the ends of the locking-arms *a*¹⁵ *a*¹⁵, pivotally secured to the outer edges of the valve-chambers. These locking-arms *a*¹⁵ *a*¹⁵ have the downwardly-extending ends *a*¹⁶ *a*¹⁶. The light open frames *a*¹⁷ *a*¹⁷ are secured to the sprinkler by screws or similar means, and the ends *a*¹⁶ *a*¹⁶ of the locking-arms are secured to the frames *a*¹⁷ *a*¹⁷ by solder, the solder *d* being fusible at a low temperature and the solder *e* being fusible at a high temperature.

In the further end of the auxiliary pipe *b*

is the automatic valve-closing mechanism, consisting of the cylinder b' , secured in the end of the pipe by the screw-threads b^2 and having the arms b^3 b^3 , supporting the bearings b^4 and b^5 , through which the rod b^6 moves lengthwise and is prevented from turning by the spline b^7 in the bearing b^6 , working in the groove b^8 , running lengthwise of the rod. The motor b^{10} , placed between the bearings b^4 and b^5 , has the elongated hub b^{11} , with the hole b^{12} for the rod b^6 and the wings b^{13} b^{13} set at an angle to revolve the hub b^{11} on the rod b^6 by the force of the fluid in the direction of the arrow, as shown in Fig. 1. The end b^{14} of the hub is in screw-threaded engagement with the screw-threaded end b^9 of the rod b^6 , and secured to the inner end of the rod b^6 by the flexible wire b^{15} is the valve-closing ball b^{16} , made preferably hollow. In the operation of my improved automatic twin sprinkler caused by fire the solder d melts at a low temperature and releases the locking-arm a^{15} , the lever a^{13} , and the low-temperature valve a^8 , which opens under the pressure of the water assisted by the spring-washer a^{12} . The water now passes through the valve-opening a^2 , the chamber a^6 , and the nozzle a^7 and strikes the deflector-plate a^8 and is deflected in the form of a spray onto the fire. The amount of water allowed to flow through the low-temperature valve-opening is governed by the number of revolutions required of the motor b^{10} on the rod b^6 to release the screw-threaded end b^9 from the hub of the motor. When the rod is released, the ball b^{16} , the wire b^{15} , and the rod are carried inward by the force of the water or other liquid until the ball b^{16} enters and closes the valve-opening a^2 and stops the flow of water, as shown in broken lines in Fig. 1. If this predetermined amount of water is not sufficient to extinguish the fire, the increased heat of the fire will melt the high-temperature solder e , opening the high-temperature valve a^5 . A continuous stream of water will now come from the sprinkler through the valve-opening a^4 , and when the fire is extinguished the water may be shut off from the main in the usual way. It is evident that the amount of water allowed to flow through the low-temperature valve could be varied by increasing or diminishing the number of threads on the rod b^6 in screw-thread engagement with the hub of the motor b^{10} and that two sprinklers could be used close together, the low-temperature sprinkler having the mechanism for automatically closing the valve after a predetermined amount of water has passed through the sprinkler without materially affecting the spirit of my invention.

Having thus described my invention, I claim as new and desire to secure by Letters Patent—

1. In a fire-extinguishing system having automatic sprinklers, means consisting of low and high temperature valves in the sprin-

kers, controlled by low and high temperature fusible solderings, and means for automatically closing the low-temperature valve after a predetermined amount of fluid has passed through the sprinkler, for the purpose as described. 70

2. In an automatic sprinkler, means consisting of a plurality of valves in the sprinkler controlled by a plurality of solderings fusible at different temperatures, and means for automatically closing one of the valves after a predetermined amount of fluid has passed through the sprinkler, for the purpose as described. 75

3. In an automatic sprinkler, means consisting of two valves in the sprinkler controlling the outlet-opening, means consisting of solder fusible at a low temperature and solder fusible at a high temperature controlling the valves, and means for automatically closing the valve controlled by the low-temperature solder after a predetermined amount of fluid has passed through the sprinkler, for the purpose as described. 85

4. In an automatic sprinkler, means consisting of two valves in the sprinkler controlling the outlet-opening, and controlled by two solderings fusible at low and high temperatures, and means consisting of mechanism connected with a motor actuated by the fluid passing through the sprinkler to close the low-temperature-controlled valve, after a predetermined amount of fluid has passed through the sprinkler, for the purpose as described. 90

5. In an automatic sprinkler, means consisting of two valves in the sprinkler controlling the outlet-opening, means consisting of mechanism to control the valves, actuated by solderings fusible at low and high temperatures, and means consisting of a ball flexibly connected to a rod, a motor in screw-thread engagement with the rod and actuated by the fluid passing through the sprinkler to release the rod and ball and close the low-temperature-controlled valve after a predetermined amount of fluid has passed through the sprinkler, for the purpose as described. 105

6. In an automatic sprinkler, the combination with the sprinkler a , of the inlet-opening a' branching into the valve-opening a^2 controlled by the valve a^3 and the valve-opening a^4 controlled by the valve a^5 , the chamber a^6 and the outlet opening or nozzle a^7 , the deflector-plate a^8 supported on the frame a^9 , the valve-chambers a^{10} a^{10} closed by the caps a^{11} a^{11} having holes for the valve-stems, the spring-washers a^{12} a^{12} to assist in opening the valves, the levers a^{13} a^{13} pivotally secured to the sprinkler and bearing on the valve-stems and secured in their closed position by the hooked ends a^{14} a^{14} passing under the ends of the locking-arms a^{15} a^{15} with the downwardly-extending ends a^{16} a^{16} pivotally secured to the sprinkler, the open frames a^{17} a^{17} secured to the sprinkler, and the solder d fusible at a low temperature and the solder e fusible at a high temperature, as described. 110 115 120 125

7. In an automatic sprinkler, the combination with the sprinkler *a*, of the auxiliary pipe *b* connected to the sprinkler by the elbow *b*¹⁷ and to a supply-pipe, the cylinder *b'* secured in the auxiliary pipe by the screw-threads *b*² and having the arms *b*³ *b*³ supporting the bearings *b*⁴ and *b*⁵, the rod *b*⁶ with the groove *b*⁸ working on the spline *b*⁷ and having the screw-threaded end *b*⁹, the motor *b*¹⁰ consisting of the hub *b*¹¹ with the hole *b*¹², the wings *b*¹³ *b*¹³ and the end *b*¹⁴ of the hub in screw-thread en-

gagement with the end *b*⁹ of the rod *b*⁶ and the wire *b*¹⁵ flexibly securing the valve-closing ball *b*¹⁶ to the rod *b*⁶, all for the purpose as described.

In testimony whereof I have signed my name to this specification in the presence of two subscribing witnesses.

FRED M. ALLEN.
